UNITED STATES PATENT OFFICE.

ANTHONY VASSELLI, OF NEWARK, NEW JERSEY, ASSIGNOR, BY MESNE ASSIGNMENTS, TO GENERAL PHONOGRAPH CORPORATION, OF NEW YORK, N. Y., A CORPORATION OF NEW YORK.

SOUND-REPRODUCING APPARATUS.

Application filed October 9, 1919. Serial No. 329,478.

To all whom it may concern:

Be it known that I, ANTHONY VASSELLI, a citizen of the United States, and a resident of the city of Newark, county of Essex, 5 and State of New Jersey, have invented a certain new and useful Improvement in Sound-Reproducing Apparatus, of which the following is a specification.

The object of my invention is to provide 10 improvements in apparatus for reproducing sound; by means of which the quality of the reproduction will be improved.

Further objects of my invention are to provide a sound-box wherein the diaphragm is more sensitive to movements of 15 the stylus caused by the engagement of the latter with the record groove; whereby chattering and blasting will be avoided; and whereby the diaphragm will be caused to 20 assume the neutral position more readily than in prior constructions, especially in reproductions of high notes.

A further object of the invention is to produce a device of the character described, 25 which is extremely simple in construction, neat and attractive in appearance, thoroughly reliable and efficient in its purpose, and inexpensive to manufacture.

With these and other objects in view to be 30 more fully set forth hereinafter, the invention consists in the novel construction, combination of elements, and arrangement of parts which will be exemplified in the construction hereinafter described in the specification and illustrated in the accompanying drawings considered together or separately.

The inventive idea involved is capable of receiving a variety of mechanical expressions, one of which for the purpose of illustrating the invention, is shown in the accompanying drawings.

The invention will be first described in connection with the accompanying drawings, 45 wherein similar reference characters are used to designate corresponding parts throughout the several views, and then more specifically defined and indicated in the appended claim.

50 In the drawings,—

Fig. 1 is a front elevation of a sound-box embodying my invention;

Fig. 2 is a section on the line 2—2 of Fig. 1;

Fig. 3 is a rear elevation; and 55

Fig. 4 is a detail section of the adjusting means.

In carrying out my invention, I provide a sound-box 1 having a diaphragm 2 mounted between rubber gaskets 3, and having a 60 tubular extension for attachment to a tone-arm, as is common.

To the center of the diaphragm is secured one end of a stylus arm 4 which may be made integral with a stylus holder 5 in 65 which a stylus 6 is secured by the usual screw 7.

Depending from the sound-box 1 is a pair of spaced ears or lugs 8, each carrying a 70 conical pointed screw 9. Each screw is provided with a lock nut 10. The screws are in axial alignment and the conical ends engage in conical sockets in opposite sides of the stylus holder between the stylus and the point of attachment of the stylus arm with 75 the diaphragm.

Carried by the stylus holder, and extending at right angles to the axial line of the screws 9 is an arm 11. The arm 11 extends under the sound-box 1, and in its free end 80 is a perforation through which extends a screw 12 which is secured within a recess 15 in the under side of the sound-box.

Surrounding the screw 12 are two helical springs 13 and 14, one in each side of the 85 arm 11 and bearing on opposite sides of the arm. One end of the spring 13 bears against the head of the screw 12, and one end of the spring 14 bears against a nut 16 lying in the recess 15, whereby the arm 11 is held normally perpendicular to the plane of the diaphragm, and the latter is normally held 90 in the neutral or central position.

The screw 12 is provided with threads 17 which engage the threaded perforation of 95 the nut 16, and has a reduced, threaded extremity 18 which is screwed into a socket in the bottom of the recess 15. The nut is provided with a lug 19 which projects through an open-ended slot 20 in the wall 100 of the sound-box and acts to prevent rotation of the nut.

The threads 17 are of twice the pitch of the threads 18, and when the screw 12

is rotated the nut 16 will be caused to travel along the screw at twice the speed that the screw will travel into or out of its socket. By this construction the springs 13 and 14 are compressed or relaxed to exactly the same extent, as depends on the direction of rotation of the screw.

If the screw be rotated in the clockwise direction the spring 13 will be compressed 10 between the head and the arm 11. As the threads 17 engaging the nut 16 are of twice the pitch of the threads 18, the nut will be drawn downward at twice the speed of the upward movement of the screw, and the 15 spring 14 will be compressed to the same extent as will the spring 13. On the reverse movement, the springs will be simultaneously relaxed and to the same extent.

When the diaphragm is flexed by the engagement of the stylus with the record groove, the tendency of one or the other of the springs 13 or 14 is to restore the diaphragm to its normal position. The springs acting on the diaphragm in the 25 axial line of the latter, make the diaphragm extremely sensitive to movements of the stylus, and as the springs perform no function other than centering the diaphragm, they can be made very light and sensitive.

30 In accordance with the provisions of the patent statute, I have described the principle of my invention, together with the apparatus which I now consider to represent the best embodiment thereof, but I 35 desire it understood that my invention is not confined to the particular form of apparatus herein shown and described, the same

being merely illustrative, and that the invention can be carried out in other ways without departing from the spirit of my invention, and therefore, I claim broadly the right to employ all equivalent instrumentalities coming within the scope of the appended claim, and by means of which objects of my invention are attained, and the 40 new results accomplished, as herein set forth, as it is obvious that the particular embodiment herein shown and described is only one of many that can be employed to attain these objects and accomplish these 45 results.

Having now described my invention, what I claim and desire to secure by Letters Patent is as follows:—

An article of the class described, comprising a sound-box casing, a diaphragm, a stylus arm attached to the diaphragm, a rearward extension on said stylus arm having a perforation, a bolt passing through the perforation, said bolt being threaded 55 into said casing, a second thread on the bolt, the second thread having a faster pitch than the first thread, a nut engaging the second thread, an elastic element between the head of the bolt and the extension, and an elastic 60 element between the extension and the nut, whereby the elements will be simultaneously 65 acted on, said casing provided with a slot, and a lug on the nut protruding into the slot for preventing rotation of the nut.

70 This specification signed this 15th day of September, 1919.

ANTHONY VASSELLI.
